ATTORNEY

UNITED STATES PATENT OFFICE.

SYDNEY P. BARKER, OF NEW YORK, N. Y.

JACK.

Application filed September 14, 1927. Serial No. 219,509.

This invention relates to jacks and while it is particularly adapted for use in connection with automobiles, the invention is of course not limited to any particular use.

5 An object of the invention is to provide a jack in which the movement of the turning parts is compounded or multiplied so as to impart a rapid movement to the lifting plunger and also give a maximum movement 10 from relatively short members, so that, while all necessary lifting movement is provided, the jack when collapsed or telescoped will occupy but a relatively small space.

15 A further object is to provide a jack of this character which is strong and compact, which can be kept lubricated and which will give the maximum of movement and power to the minimum of power expended.

With these and other objects in view, the 20 invention consists in certain novel features of construction and combinations and arrangements of parts which will be more fully hereinafter described and pointed out in the claims.

25 In the accompanying drawings—

Figure 1 is a view in vertical longitudinal section showing the parts of my improved jack in their lowermost or collapsed position;

Figure 2 is a similar view showing the 30 members of the jack partially extended;

Figure 3 is an enlarged view in transverse section on the line 3—3 of Figure 1.

Figure 4 is a top plan view of certain details.

35 1 represents a hollow base and 2 a tubular upright integral with the base and of general cylindrical form. The hollow base 1 is closed by a removable base plate 3 secured thereto by screws or other attaching means 4 and 40 having webs 5 thereon which support a ball 6. 7 represents a horizontally positioned gear wheel having a socket member 8 central in the bottom thereof which has a thrust bearing on the ball 6.

45 A drive shaft 9 projects through a bearing 10 in the base 1 and has a pinion 11 thereon meshing with the gear wheel 7, and the outer end of this shaft 5 may be made angular, as shown at 12, to receive a wrench or crank or 50 other suitable device for imparting a rotary motion thereto. 13 is a removable collar located on the shaft 9 and adapted to removably secure the shaft 9 in the base 1.

A vertical post 14 is fixed to the center of 55 gear 7 and turns therewith. This post 14 is located centrally in the tubular upright 2,

is externally screw-threaded and is hollow. A collar 15 is secured in the upper end of the post 14 and has an angular opening 16 therein so as to receive an angular stem 17 on a screw 60 head 18. The screw head 18 is of appreciably greater diameter than the post 14 and is externally screw-threaded and meshes with the internal screw threads 19 in a hollow cylindrical plunger 20.

65 This plunger 20 may carry any suitable saddle or head 21 at its upper end and is preferably of a length to fit approximately within the upright 2 when lowered or collapsed. A sleeve 22 is disposed between the post 14 and 70 the plunger 20 and this sleeve has internal screw threads 23 at its lower end which engage the external screw threads of the post 14.

The parts are so arranged that the upper 75 end 24 of the sleeve 22 engages under the screw head 18. This sleeve 22 is provided with one or more external longitudinal keys 24 which move in keyways 25 in an internally threaded portion of the plunger 20 so as to prevent independent rotary movement of 80 these parts.

A shell 26 is interposed between the plunger 20 and the upright 2, and this shell is provided with a keyway 27 receiving a key 28 on the plunger 20. The keyway 27 extends 85 throughout the major portion of the shell but said keyway terminates short of the upper end of the shell so that a shoulder 29 is provided on the shell and is engaged by the key 28 when the latter reaches the position shown 90 in Figure 2, so that a continued upward movement of the plunger will draw the shell with it and this shell will cover the joint between the plunger 20 and the sleeve 22 and strengthen the telescoping parts and cover 95 their joint when the jack is extended.

I also provide in the shell 26 an external longitudinal groove 30 which extends from its upper end to a point adjacent its lower end, and I locate a screw or other removable 100 device 31 in the upright 2 which rides in this groove and which engages a shoulder 32 at the lower end of the groove to prevent further upward movement of the shell, or, in other words, to limit the upward movement thereof. 105

In describing my improved device I have referred to the parts as being "tubular", "cylindrical" etc., and it is obvious that the invention is not to be limited to the shape of the parts as this may be varied. I have also referred to certain parts as having "keys" and others as having "keyways" and "grooves", 110

and this is of course to be understood as describing the illustrations only as these parts may be reversed as desired.

The operation is as follows:

- 5 Assuming the parts to be in the position shown in Figure 1, a turning movement of shaft 9 in one direction will, through the medium of pinion 11 and gear wheel 7, impart rotary motion to the post 14. As this post has 10 screw-threaded engagement with the sleeve 22 it will cause said sleeve to move upwardly. Furthermore, by reason of the coupled engagement of the angular stem 17 to post 14, this stem will likewise be turned, and the 15 screw 18 thereon meshing with the internal screw threads in the plunger 20 will cause the plunger to move upward.

Thus it will be noted that the turning movement of post 14 is compounded in that it not 20 only imparts a direct lifting action to the sleeve but also a lifting action to the plunger 20 so that rapid elevation of the plunger is had. When the plunger reaches the position shown in Figure 2, the key 28 will cause the 25 shell 26 to move upwardly, covering the juncture between the plunger and the sleeve and reinforcing the device as a whole in its telescoping action. To collapse the jack the shaft 9 is turned in the opposite direction and the 30 parts will be turned downwardly and mainly enclosed within the upright 2, as clearly indicated in Figure 1.

While I have illustrated what I believe to 35 be a preferred embodiment of my invention, it is obvious that various alterations and changes might be made in the general form of the parts described without departing from the invention and hence I do not limit myself to the precise details set forth but consider 40 myself at liberty to make such changes and alterations as fairly fall within the spirit and scope of the appended claims.

I claim:

1. A jack, including a hollow upright, a 45 rotary externally screw-threaded hollow post in the upright, means for turning the post, a vertically movable plunger, an angular stem telescoping in the post, a screw head on the stem engaging the internal threads of the 50 plunger, and a sleeve on the post engaging the screw head and having internal screw-threaded engagement with the post.

2. A jack, including a hollow upright, a 55 rotary externally screw-threaded hollow post in the upright, means for turning the post, a vertically movable plunger, an angular stem telescoping in the post, a screw head on the stem engaging the internal threads of the 60 plunger, a sleeve on the post engaging the screw head and having internal screw-threaded engagement with the post, and a shell between the plunger and the upright and caused to move with the plunger after the latter has moved a defined distance.

- 65 3. A jack, including a hollow upright, a

rotary externally screw-threaded hollow post in the upright, means for turning the post, a vertically movable plunger, an angular stem telescoping in the post, a screw head on the stem engaging the internal threads of the 70 plunger, and a sleeve on the post engaging the screw head and having internal screw-threaded engagement with the post, said upright and post held against longitudinal movement and all other of said parts keyed 75 together whereby an independent rotary movement is prevented.

4. A jack, including a hollow post, a rotary externally screw-threaded hollow post in the upright, means for turning the post, 80 a vertically movable plunger, a plurality of means operated by the turning movement of the post to impart longitudinal movement to the plunger and compound said movement, and a shell between the plunger and the upright and caused to move with the plunger after the latter has moved a defined distance, said upright and post held against longitudinal movement and all other of said parts keyed together whereby independent rotary 90 movement is prevented.

5. A jack, including a hollow upright, a rotary externally screw-threaded hollow post in the upright, means for turning the post, a vertically movable plunger, an angular 95 stem telescoping in the post, a screw head on the stem engaging the internal threads of the plunger, a sleeve on the post engaging the screw head and having internal screw-threaded engagement with the post, and a 100 shell between the plunger and the upright and caused to move with the plunger after the latter has moved a defined distance, said upright and post held against longitudinal movement and all other of said parts keyed 105 together whereby independent rotary movement is prevented.

6. A jack, including a hollow base, an upright on the base, a removable plate secured to the bottom of the base, a gear wheel having a thrust bearing on said base plate, a pinion engaging the gear wheel, a shaft secured to the pinion and projecting through the base, an externally screw-threaded hollow post fixed to turn with the gear wheel, an 110 internally screw-threaded plunger, a sleeve having internal screw-threaded engagement with the post, a stem mounted to turn with the post and telescope therein, a screw head on the stem engaging the internal threads of the 115 plunger and engaged by the upper end of the sleeve, and said sleeve and plunger keyed together.

7. A jack, including a hollow base, an upright on the base, a removable plate secured 125 to the bottom of the base, a gear wheel having a thrust bearing on said base plate, a pinion engaging the gear wheel, a shaft secured to the pinion and projecting through the base, an externally screw-threaded hollow 130

post fixed to turn with the gear wheel, an internally screw-threaded plunger, a sleeve having internal screw-threaded engagement with the post, a stem mounted to turn with the post and telescope therein, a screw head on the stem engaging the internal threads of the plunger and engaged by the upper end

of the sleeve, and said sleeve and plunger keyed together, and a shell keyed to the outside of the plunger.

10

Signed at New York, in the county of New York and State of New York this 12th day of September, A. D. 1927.

SYDNEY P. BARKER.
